UNITED STATES PATENT OFFICE.

WILLIAM L. MANN, OF NEW YORK, N. Y.

DESIGN FOR A BADGE, PIN, BUTTON, OR A SIMILAR ARTICLE OF MANUFACTURE.

61,204.

Specification for Design.

Patented July 11, 1922.

Application filed February 12, 1921. Serial No. 444,611. Term of patent 3½ years.

To all whom it may concern:

Be it known that I, WILLIAM L. MANN, a citizen of the United States, residing in the borough of Manhattan, city, county, and State of New York, have invented a new, original, and ornamental Design for Badges, Pins, Buttons, or Similar Articles of Manufacture, of which the following is a specification, reference being had to the accompanying drawing, forming part thereof.

The figure is a plan view of a badge, pin,

button or a similar article of manufacture, showing my new design.

The background of the emblem around the white figure and lettering is red, blue and red, as indicated symbolically in the drawing in accordance with the rules.

I claim:

The ornamental design for a badge, pin, button, or a similar article of manufacture, as shown.

WILLIAM L. MANN.
